UNITED STATES PATENT OFFICE.

MARK N. SMITH, OF YONKERS, NEW YORK, ASSIGNOR OF ONE-HALF TO JOSEPH R. DUMONT, OF KANSAS CITY, MISSOURI.

COIN-OPERATED LOCK.

Application filed January 31, 1921, Serial No. 441,185. Renewed August 31, 1922. Serial No. 585,561.

To all whom it may concern:

Be it known that I, MARK N. SMITH, a citizen of the United States, and a resident of Yonkers, in the county of Westchester and 5 State of New York, have invented a new and useful Coin-Operated Lock, of which the following is a specification.

My invention relates to coin operated locks and its principal object is to provide 10 a lock of this character, principally adapted for use in public places such as toilets or in other places where a small charge is usually made for the use of such places.

A further object of the invention is to 15 provide a lock which may be operated by coins of a predetermined denomination and which cannot be operated by slugs of less weight and diameter than the coin or other fraudulent means.

It is also an object of the invention to 20 provide a coin operated lock having means for indicating whether or not the toilet or other public place is in use, and which, when in use, will prevent a second coin 25 from being inserted therein.

Still another object of the invention is to 30 provide a lock of this character which may be operated by the attendant without the use of a coin.

With the preceding and other objects and 35 advantages in mind, the invention consists in the novel combination of elements, construction and arrangement of parts and operations to be more fully described, claimed 40 and illustrated in the accompanying drawings, wherein:

Figure 1 is a rear elevation of the lock, parts being broken away;

Figure 2 is a face view of the removable 45 rear wall of the lock and the lock parts carried thereby;

Figure 3 is a view partly in elevation and partly in vertical cross section of the lock assembled;

Figure 4 is a top plan view of the lock;

Figure 5 is a bottom plan view of the same;

Figures 6, 7 and 8 are perspectives of various elements embodied in the invention;

Figure 9 is a fragmentary elevation of 50 the lock section disclosed in Figure 1;

Figure 10 is a front elevation of the latter, having parts broken away;

Figure 11 is a side elevation of the lock in operative position; and 55

Figure 12 is a perspective of the attendant's key used in connection with the invention.

Referring in detail to the drawings 60 wherein similar characters of reference designate similar parts throughout the several views, the numeral 5 designates a door to which my improved lock is applied. Mounted upon the outer face of the door 5 is a plate 6 carrying an upturned flange 7 at its 65 upper edge which is spaced from the door 5.

Passing transversely through the door 5 from the inner face thereof is the shaft 8 of a door knob 9. The inner end of this shaft 8 extends within a casing 10 secured to the 70 outer face of the plate 6. Arranged in this casing 10 and operatively connected with the shaft 8 is a spring lock mechanism 11. One end of this shaft 8 projects through the casing 10 and fixed thereto is a 75 vertically disposed longitudinally curved arm 12 which is for a purpose to be herein-after specified.

The numeral 13 designates a casing which 80 is open at the rear thereof and is formed with a down-turned flange 14 at the rear of its upper end which is removably held between the flange 7 and the door 5. A bar 15 extends transversely across the casing adjacent its lower end and is secured to the 85 door 5 by screws or other fastenings 16.

Mounted in the casing 13 is a conventional lock designated in its entirety at 17 and includes a swinging spring held member 18 and a sliding locking bolt 19 movable 90 transversely of the casing 13. As is clearly shown in Figure 8, the locking bolt 19 is provided with a slot 20 at its rear end having pivotal and slidable connection with the swinging member 18. The shaft 21 of a 95 door knob 22 extends transversely through the casing 13 from the outside thereof and is fixed to rotate with the swinging member 18. Thus, upon rotation of the door knob 22, the swinging member 18 will be 100 swung or rocked to retract the locking bolt 19.

As is shown in Figure 2, the lock mechanism 11 includes a spring held swinging member 23 identical to the swinging member 18 and which carries, at its upper end, 105

a laterally disposed pin 24 which projects within the slot 20 of the locking bolt 19. It will thus be obvious that upon rotation of the knob 9, the locking bolt will be retracted.

Extending vertically within the casing 13 and in close proximity to the forward wall thereof is a coin chute or guide 25. This coin chute or guide is secured, at its upper end, to the casing 13 by fastenings 26, while its lower end terminates in a plate 27 engaged in slots 28 of outstanding lugs 29 formed on the inner face of the forward wall of the casing 13. A coin receiving slot 30 is provided in the top of the casing 13 and is disposed in vertical alinement with the chute or coin guide 25.

Pivoted to the plate 27, at one edge thereof, is a trip 31, the forward end of which is normally disposed in the path of the coins passing through the coin chute or guide 25. The opposite end of this trip 31 is weighted as at 32 so that the trip will be normally disposed in the annular position shown in Figure 1. Formed upon the inner face of the part 32 is a pair of laterally disposed spaced lugs 33 whose opposed faces are beveled to present divergent surfaces 34 as shown in Figure 7.

Vertically movable in the casing 13 is a stem or shank 35, carrying at its upper end, a rectangular head or locking element 36 which normally engages the swinging member 18 and locks the same against movement. The lower end of this stem or shank 35 is formed with a right angularly disposed foot 37 which is engaged between the spaced lugs 33 for pivotal movement. In order to limit the pivotal movement of the trip 31 in one direction, an abutment 32' is formed upon the forward wall of the casing 13 above the point of pivotal connection of this trip 31 with the plate 27 and is provided with a beveled lower wall 33' with which the part 32 of the trip 31 abuts.

Pivoted to the plate 27, at its opposite edge, is a finger or coin holding element 38, the lower end of which projects downwardly at an angle and is in the path of the coins passing through the chute or guide 25. The upper end of this finger or coin holding element 38 is pivotally connected with the locking bolt 19 as indicated at 39.

From the disclosure thus far given, it follows that when a coin is inserted in the slot 30, it passes downwardly through the chute or guide 25 and engages the forward end of the trip 31, raising the latter to the dotted line position and lifting the stem or shank 35 to a position where the locking element 36 will not engage the swinging member 18; the coin continuing downwardly is engaged by the finger 38 and is held in this position by the finger 38 and the trip 31. The knob 22 may be now rotated to

retract the locking bolt 19. This moves the finger 38 away from the coin and the latter drops to the bottom of the casing, and the trip 31 and locking element 36 return to their normal position.

Horizontally and longitudinally movable in a guide-way 40 at the upper end of the casing 13 is a block or carriage 41 carrying a laterally disposed pin 42 at one end thereof. Carried upon the upper face of this block or carriage 41 is suitable indicia 43 which reads, in this instance, "In" "Out." The top wall of the casing 13 is provided with a sight opening 44 with which the words "In" or "Out" are adapted to register.

Carried by the inner end of the shaft 21 is an upstanding arm 45 having its upper end engaged with the pin 42. Thus, after the lock has been operated, as hereinabove described, the rotation of the shaft 21 will move the arm 45 forwardly to move the block or carriage 41 to a position where the word "In" will register with the sight opening.

The upper end of the arm 12 is disposed at the opposite end of the casing and is in the path of the pin 42 when the block or carriage is in its advanced position. Thus, upon rotation of the shaft 8 the arm 12 will engage the pin 42 and move the block or carriage to the position shown in Figure 1 and in which position the word "Out" will register in the sight opening.

A cover plate 46 is arranged in the casing 13 to overlie the various elements to retain the same in their respective positions.

In order that an attendant or other authorized person may operate the lock without the aid of a coin, I provide a vertically movable stem 47 which passes through a vertical opening or guide 48 of a cross bar 49 in the casing 13. Formed within the casing 13 in alinement with the stem 47 is a rectangular casting 50 having a vertical bore 51 which slidably receives the lower end of the stem 47 and which registers with a key opening 52 in the bottom wall of the casing 13. This bore 51 is formed with a laterally disposed recess 53 at its lower end.

The stem 47 carries a collar 54 which normally rests on the casting 50 and supports this stem in a position where its upper end will touch the weighted end of the trip 31.

The key designated at 55 and shown in Figure 12 includes lugs 56 that are disposed at right angles to each other. In unlocking the lock by means of this key, the latter is inserted into the bore 51 and in which position the lower lug 56 will be disposed in the recess 53. The key is then rotated a quarter turn so that this lug will pass out of the recess 53 and when in this position, the key 55 is raised vertically to lift the stem 47 which rocks the trip 31 on its pivot and raises the locking element 36.

- In order to gain access to the interior of the casing for collecting the coins therefrom, the casing 13 is provided with a circular opening 57 normally closed by a removable door 58 carrying a lock 59, the locking bolt of which engages in a recess 60 in the bar 49, while, at its lower end this door or closure carries a lip 61 engageable behind the forward wall of the casing.
- 10 It is to be understood that the form of my invention herein shown and described is to be taken as a preferred example of the same, and that various changes in the shape, size and arrangement of parts may be 15 sorted to without departing from the spirit of the invention or the scope of the subjoined claims.
- Having thus described my invention, what I claim as new and desire to secure 20 and protect by Letters Patent of the United States, is:—
1. A coin operated lock including a casing, independently rotatable door knob shafts journaled in the casing and extending from 25 opposite sides thereof, a lock mechanism associated with the door knob shafts and including spring held swinging members fixed to swing with the shafts, a locking bolt adapted to be retracted by either of the 30 swinging members, means for conducting coins through the casing, a pivoted trip disposed in the path of movement of the coins, and a longitudinally movable locking element positioned behind one of the swinging 35 members and normally locking the same against movement and moved in a position to permit the swinging member to move upon actuation of the trip by a coin.
2. A coin operated lock including a casing, 40 independently rotatable door knob shafts journaled in the casing and extending from opposite sides thereof, a lock mechanism associated with the door knob shafts and including spring held swinging members fixed to swing with the shafts, a locking bolt adapted to be retracted by either of the 45 swinging members, means for conducting coins to the casing, a pivoted trip disposed in the path of movement of the coins, a longitudinally movable locking element 50 positioned behind one of the swinging members and normally locking the same against movement and moved to a position to permit the swinging member to move upon actuation of the trip by a coin, and a pivoted finger disposed to one side of the trip having 55 one end pivotally connected with the locking bolt and with the trip adapted to hold the coin until the locking bolt has been 60 retracted.
3. A coin operated lock including a casing, 65 independently rotatable door knob shafts journaled in the casing and extending from opposite sides thereof, a lock mechanism associated with the door knob
- shafts and including spring held swinging members fixed to swing with the shafts, a locking bolt adapted to be retracted by either of the swinging members, means for conducting coins through the casing, a trip 70 pivoted intermediate its ends and having one end weighted and its opposite end disposed in the path of movement of the coins passing through the casing, a vertically movable stem having its lower end pivotally connected with 75 the weighted end of the trip, a locking element carried by the upper end of the stem and normally engaged with one of the swinging members to hold the same against movement, the actuation of the trip by a coin 80 causing the stem to be moved upwardly to move the locking element to a position where the swinging member will not engage the same.
4. A coin operated lock including a casing, 85 independently rotatable door knob shafts journaled in the casing and extending from opposite sides thereof, a lock mechanism associated with the door knob shafts and including spring held swinging 90 members fixed to swing with the shafts, a locking bolt adapted to be retracted by either of the swinging members, means for conducting coins through the casing, a trip pivoted intermediate its ends and having one 95 end weighted and its opposite end disposed in the path of movement of the coins passing through the casing, a vertically movable stem having its lower end pivotally connected with the weighted end of the trip, a locking element carried by the upper end of the stem and normally engaged with one of the 100 swinging members to hold the same against movement, the actuation of the trip by a coin causing the stem to be moved upwardly 105 to move the locking element to a position where the swinging member will not engage the same, and a coin holding finger pivoted to one side of the trip and having its upper end pivotally connected with the locking 110 bolt.
5. A coin operated lock including a casing, 115 independently rotatable door knob shafts journaled in the casing and extending from opposite sides thereof, a lock mechanism associated with the door knob shafts and including spring held swinging members fixed to swing with the shafts, a locking bolt adapted to be retracted by either of the 120 swinging members, a coin chute in the casing, a trip pivoted to one side of the coin chute and adapted to be rocked by coins passing through the chute, a longitudinally movable locking element normally engaged with one of the swinging elements and 125 moved away from the latter upon actuating of the trip, a coin holding finger pivotally mounted in the path of the coins and disposed to one side of the trip and having pivotal connection with the locking bolt where- 130

upon retraction of the locking bolt the finger will be moved away from the coin to permit the same to drop and the subsequent return of the trip and locking element to normal position.

6. A coin operated lock including a casing, independently rotatable door knob shafts journaled in the casing and extending from opposite sides thereof, a lock mechanism associated with the door knob shafts and including spring held swinging members fixed to swing with the shafts, a locking bolt adapted to be retracted by either of the swinging members, a coin chute in the casing, a trip pivoted to one side of the coin chute and adapted to be rocked by coins passing through the chute, a longitudinally movable locking element normally engaged with one of the swinging elements and moved away from the latter upon actuation of the trip, a coin holding finger pivotally mounted in the path of the coins and disposed to one side of the trip and having pivotal connection with the locking bolt where upon retraction of the locking bolt, the finger will be moved away from the coin to permit the same to drop and the subsequent return of the trip and locking element to normal position, a block slidably mounted in the casing and carrying indicia to indicate whether or not the lock has been operated, and arms fixed to the shafts and adapted to move the block in one direction upon rotation of its shaft and adapted to move the block in the other direction upon rotation of the other shaft.

7. A coin operated lock including a casing, independently rotatable door knob shafts journaled in the casing and extending from opposite sides thereof, a lock mechanism associated with the door knob shafts and including spring held swinging members fixed to swing with the shafts, a locking bolt adapted to be retracted by either of the swinging members, means for conducting coins through the casing, a pivoted trip disposed in the path of movement of the coins, a longitudinally movable locking element positioned behind one of the swinging members and normally locking the same against movement and moved to a position to permit the swinging member to move upon actuation of the trip by a coin, a vertically movable stem mounted in the casing and having one end positioned against one end of the trip, and a key insertable in the bottom of the casing whereby to raise the stem to rock the trip and thereby move the locking element to inoperative position.

60 8. A coin operated lock including a casing, independently rotatable door knob shafts journaled in the casing and extending from opposite sides thereof, a lock mechanism associated with the door knob shafts and including spring held swinging members fixed

to swing with the shafts, a locking bolt adapted to be retracted by either of the swinging members, a vertically disposed coin chute in the casing, pivoted elements disposed at opposite sides of the chute adapted to be engaged by the coins passing through the chute, one of the pivoted elements being pivotally connected with the locking bolt, and a locking element normally engaging one of the swinging members to hold the same against movement and adapted to be moved to inoperative position upon pivotal movement of the other pivoted member.

9. A coin operated lock including a casing, independently rotatable door knob shafts journaled in the casing and extending from opposite sides thereof, a lock mechanism associated with the door knob shafts and including spring held swinging members fixed to swing with the shafts, a locking bolt adapted to be retracted by either of the swinging members, a vertically arranged coin chute in the casing, a normally angularly disposed trip pivotally supported at one side of the chute, a pair of spaced beveled lugs formed upon one face of the trip, a vertically movable shank having its lower end disposed at right angles and pivotally engaged between the lugs, a locking element carried by the upper end of the shank and normally engaging one of the swinging members to hold the same against movement, and a pivoted finger disposed to one side of the trip and disposed in the path of the coins passing through the chute and adapted with the trip to hold the coin until the retraction of the locking bolt when the finger will be disengaged from the coin to permit the latter to drop.

10. A coin operated lock including a casing, independently rotatable door knob shafts journaled in the casing and extending from opposite sides thereof, a lock mechanism associated with the door knob shafts and including spring held swinging members fixed to swing with the shafts, a locking bolt adapted to be retracted by either of the swinging members, a vertically arranged coin chute in the casing, a normally angularly disposed trip pivotally supported at one side of the chute, a pair of spaced beveled lugs formed upon one face of the trip, a vertically movable shank having its lower end disposed at right angles and pivotally engaged between the lugs, a locking element carried by the upper end of the shank and normally engaging one of the swinging members to hold the same against movement, a pivoted finger disposed to one side of the trip and disposed in the path of the coins passing through the chute and adapted with the trip to hold the coin until the retraction of the locking bolt when the finger will be disengaged from the coin to

permit the latter to drop, a vertically movable rod normally engaging the lower end of the trip, and a key insertable through the bottom of the casing whereby to actuate the 5 trip without the aid of a coin.

11. A coin operated lock including a casing, a slidable locking bolt mounted therein, manually operable swinging members operatively connected with the locking bolt 10 whereby to retract the locking bolt, a coin guide mounted in the casing, pivoted elements disposed in the path of the coins passing through the guide and one of which has pivotal connection with the locking bolt, and 15 a longitudinally movable locking element normally disposed in the path of one of the swinging elements to hold the latter against movement and having operative connection with the other pivoted element.
- 20 12. A coin operated lock comprising a casing, a locking bolt slidably mounted therein, manually operable swinging members operatively connected with the locking bolt

whereby to retract the latter, and coin operated means in the casing including a longitudinally movable locking element normally engaged with one of the swinging members to hold the latter against movement and having operative connection with the coin operated means whereby to move the locking element to a position to permit the operation of said swinging member.

13. A coin operated lock comprising a casing, a slidable locking bolt mounted therein, manually operable means for retracting the locking bolt, a coin guide in the casing, pivoted elements disposed in the path of the coins passing through the casing and one of which being pivotally connected with the locking bolt, and a longitudinally movable 35 element normally engaged with one member of the retracting means whereby to prevent retraction of the locking bolt and having operative connection with one of the pivoted elements.

MARK N. SMITH.
